UNITED STATES PATENT OFFICE.

CARL A. KELLOGG, OF BROOKLYN, NEW YORK.

PRINTING PRESS.

Application filed March 26, 1919. Serial No. 285,339.

To all whom it may concern:

Be it known that I, CARL A. KELLOGG, a citizen of the United States, residing in the city of New York, borough of Brooklyn, county of Kings, and State of New York, have invented certain new and useful Improvements in Printing Presses, of which the following is a specification.

This invention relates to printing presses, and among the objects of the invention, though not the exclusive ones, may be enumerated: The provision of a printing machine wherein one of the members of the printing couple is movable toward and away from the other, to allow of the passing of the form rollers therebetween, and in which machine the moving member of the couple is so supported and guided in its operations that free access may be had from the side of the machine to the form bed to allow of the ready positioning of the form within or its removal from the bed; the provision of a machine having a printing couple, one or both of the members of which are movable toward and away from one another, and with which moving member or members is associated cushioning means, preferably operating through leverage connections, for the purpose of taking up the shock between the members of the printing couple when they are brought together into printing cooperation and for counterbalancing the movable member; and, the provision, in a printing machine of the character described, of means for taking up lost motion and wear in the operating parts of the movable printing couple member or members.

Features of the invention other than those specified will be apparent from the hereininafter detailed description taken in conjunction with the accompanying drawings.

In the accompanying drawings I have illustrated one practical embodiment of the invention, but the construction therein shown is to be understood as illustrative only, and not as defining the limits of the invention.

Figure 1 is a side elevation of a portion of a printing press showing the present invention as associated therewith, the operating members of the printing couple being shown in this figure on impression; and.

Figure 2 is a view similar to Figure 1, but illustrating the parts in the positions which they assume when off impression.

Referring to the drawings, A designates

upright side portions of the frame of a printing machine, which, in the form of the invention shown, has mounted therein a fixed form bed B, and a movable platen C. 60 The platen is of a rocking type of the general character disclosed in the pending application of John Caplinger, Serial No. 254,162, and, as in the prior application, is movable toward and away from the fixed form bed and is adapted to be rocked while on impression by virtue of its operating member which is in the form of a crank shaft D, of which d is the shaft, and d' the crank. The shaft d is mounted for rotation 65 between upper and lower journals E and E' which are mounted for vertical adjustment in slides f, formed in the frame A. Correct vertical adjustment may be had in the journals through the manipulation of adjusting 70 screws e and e' which thread into the frame and have their heads bearing against the opposed journal boxes E and E' respectively. Through the manipulation of the adjusting screws e and e', the crank shaft 75 may be raised or lowered for the purpose of obtaining proper cooperation between the curved impression surface c of the platen and a form adapted to be supported by the form bed B. Moreover, associated with the 80 lower journal E' are a pair of compression springs g, the purpose of which is to take up any lost motion due to wear between the journal bearing and the crank shaft. If there is any looseness in the bearings the 85 platen will pound when it comes into contact with the bearers, if such are used, or with the type where no bearers are employed. The springs take the weight of the platen and are sufficiently strong to hold the bearing E' in 90 engagement with the shaft so that all lost motion is taken up and, as the boxes E and E' do not meet, the springs g will have a 95 direct pressure or lifting effect on the shaft.

The platen is guided for operation by 100 cross-heads H, positioned at either side of the platen, and pivotally secured thereto at h. Side openings are provided in the upright portions at the opposite sides of the platen, and the vertical edges a of the openings serve as guides for the opposite ends of the cross-heads H. Thus, through the operation of the cross-heads with their guides, the platen is guided for vertical movement when it is operated upon by the 105 crank shaft D. It will thus be seen that the platen is pivotally supported by the crank

2. shaft D at a point eccentric to its curved impression surface *c*, which latter is struck with a comparatively large radius greatly exceeding the distance of the axis of the 5 crank *d'* from the impression surface *c*, so that a comparatively slight extent of angular or rotary movement of the crank shaft, will suffice to move said platen to an extent sufficient to cause the platen to completely 10 traverse the form to complete the impression.

The advantages of guiding the platen by cross-heads as described, is that when the platen is off impression free access may be 15 had to the form bed from the side of the machine, so that the form may be readily positioned in or removed therefrom. The advantage of this will be apparent to those skilled in the art and the present invention 20 thus overcomes a disadvantage in the press of the co-pending Caplinger application hereinbefore referred to, wherein the guides for the platen are at the side of the form bed and preclude the positioning of a form into 25 the machine from the side thereof.

When the parts become worn in platen presses of the character described, there is more or less shock when the members of the printing couple come together for impression due mainly to lost motion, but in 30 the accompanying drawings, I have diagrammatically shown means whereby this may be obviated. The means in question consists of a pair of bell cranks having work 35 arms *i* and power arms *i'*. These bell cranks are fulcrumed at *i²* and have link connections *i³* pivotally secured to the ends of their work arms and to the cross-heads *H*. Associated with the power arms of the bell 40 cranks are springs I through which extend guide rods I' and the compression on these springs may be varied by adjusting nuts *i⁴* threaded on the arms. The compression on the springs I is sufficiently great to take the 45 weight of the platen and cross-heads, and to serve to slightly hold back the platen as it is forced down by the crank shaft. Thus, as the platen goes down on impression, the tension on the springs I is increased until, 50 at the time the platen goes on impression it is checked sufficiently to overcome its momentum, thereby allowing of the members of the couple to come into contact at high speeds without shock.

55 It will be noted that in the showing made, the work arms of the bell cranks are of greater length than the power arms, and this construction allows of relatively extensive movement of the platen with proportionately little movement of the springs. The springs are thus enabled to better maintain their adjustment and will last much longer than if they were directly subjected to great movement from the platen.

60 65 It will be apparent from the foregoing

description that the present invention embodies many features of advantage over the prior art. The connections and operation of the platen is such that there is no lost motion in any of the bearings, in the direction of pressure of these parts, thereby permitting of the operation of the machine at high speed without jar or vibration. The springs under the bearings of the crank shaft take up lost motion at these points and may also be made adjustable, and the springs on the connections of the cross-heads similarly take up any looseness in the platen bearing on the crank shaft, and carry the weight of the platen and cross-heads. The platen is pivotally associated with the cross-heads which allow the platen to be rocked over the form bed while guided by the cross-heads, and, if desired, the sliding connection between the cross-heads and the frame of the machine may be made adjustable to take up wear. While the springs I are shown as connected to the cross-heads through bell-cranks and links, they may be directly connected to the platen without departing from the spirit of this invention.

I am aware that weights for counter-balancing platens have been employed, but in every instance these weights do not prevent shock and jar when the platen contacts with the form, the function of such weights being merely to balance the weight of the platen as it is tilted back to allow of the placement of the sheet to be printed and do not serve to lift the platen.

I am also aware that springs have been used to take up the weight of a lifting cylinder which prints on but one of a number of its revolutions, but, such cylinders lift but very little, and the construction is such that the springs will not stand up for any length of time if the cylinder is raised high enough to allow of a form roller to pass between the cylinder and the bed as is necessary in a platen press.

While it is preferred to employ springs I in the manner specified, it is perfectly feasible to dispense with the springs and use an air cushion instead, i. e., to control the operation of the bell-cranks through pneumatic means, and, in practice, either a spring or pneumatic means can be employed.

The foregoing description, and in the accompanying drawings, the invention is described as embodying both the spring connection with the crank shaft and the spring and bell cranks as connections with the platen. When both these features are employed together, a high efficiency press results, but, if desired, either one of these features may be employed without necessarily embodying the other. Moreover, while it is preferable to support the platen at both ends thereof, a very satisfactory structure results if the spring cushioning means is asso-

ciated with only the leading end of the platen, i. e., the end which first engages with the form on impression, since, after the platen is once on impression, the mere rocking thereof will not cause jar or shock.

Having thus fully described the invention, what I claim as new, and desire to secure by Letters Patent is:

1. A printing press embodying a printing couple, means for moving one member of the couple toward and away from the other to allow a form roller to pass over one of said members and to bring said members on and off impression and rock one of said members over the other while on impression, and means for counterbalancing said movable member at all times.

2. A printing press embodying a printing couple, one member of which is positioned above the other and is adapted to be bodily raised and lowered off and on impression, means for rocking the said member while on impression, and means for counterbalancing the weight of said member at all times.

3. A printing press embodying a form bed and a platen, a slideable cross-head to which the platen is pivoted, and means for operating the platen to move it toward and away from the form bed and rock it over the form bed while on impression, said cross-head, when the platen is off impression, allowing the positioning of a form onto the form bed from the side of the machine and beneath the cross-head, and means for counterbalancing the weight of the cross-head and platen.

4. A printing press embodying a form bed and a platen, a slideable cross-head to which the platen is pivoted, and means for operating the platen to move it toward and away from the form bed and rock it over the form bed while on impression, said cross-head, when the platen is off impression, allowing the positioning of a form onto the form bed from the side of the machine and beneath the cross-head, and cushioned leverage connections for counterbalancing the weight of the cross-head and platen, and for precluding shock when the platen goes off impression.

5. In a printing machine a printing couple, operating means for moving one member of the printing couple toward and away from the other to move the movable member on and off impression and to positively limit the movement of the movable member independently of contact between said members, and means for the automatic taking up of lost motion in the operating means to prevent shock when the members go on impression.

6. A printing press embodying a printing couple, one member of which is movable toward and away from the other, to allow of the passage of a form roller between said

members in combination with means to prevent shock embodying at least one lever pivoted to one of said members, and a spring associated with said lever for preventing shock when the members are brought together.

7. A printing press embodying a printing couple, one member of which is movable toward and away from the other, a shaft and bearings for automatically operating the movable member and resilient means for automatically taking up lost motion between the shaft and bearings, in combination with means for counterbalancing the movable member.

8. A printing press embodying a platen, means for bodily raising and lowering the platen to move it off and on impression and for rocking the platen while on impression, and means for counterbalancing the platen at all times.

9. A printing press embodying a platen and cushioned levers for counterbalancing the platen and to take the shock of the platen when going on impression.

10. A printing press embodying a platen, bell crank levers, the long arms of which are operatively connected with the platen, and cushioned means associated with short arms for counterbalancing the weight of the platen.

11. A printing press embodying a printing couple mounted for relative movement, and cushioned leverage means for preventing shock or jar between the members of the couple when going on impression.

12. In a printing machine, a printing couple embodying a movable member provided with a trunnion, sectional bearings embracing the trunnion and means for automatically taking up the lost motion in bearing and trunnion.

13. In a printing machine, a printing couple embodying a movable member provided with a trunnion, sectional bearings embracing the trunnion and means for automatically taking up the lost motion in bearing and trunnion, in conjunction with means independent of the said automatic means and the journal for supporting the weight of the movable member.

14. In a printing machine, a printing couple embodying a movable member provided with a trunnion, sectional bearings embracing the trunnion and means for automatically taking up the lost motion in bearing and trunnion, a plurality of levers pivoted to the movable member and springs associated with said levers for impelling the levers in a direction to counter balance the weight of the movable member and assist said automatic means in taking up lost motion.

15. In a printing machine, a printing couple embodying a movable member pro-

- vided with a trunnion, sectional bearings embracing the trunnion and means for automatically taking up the lost motion in bearing and trunnion, a plurality of bell 5 crank levers, one arm of each lever being pivoted to the movable member, and a spring associated with the other arm of each lever for counter balancing the weight of the movable member and also assisting said 10 means in taking up lost motion.
16. In a printing machine, a platen operating means for unyieldably forcing the platen on impression, and means for automatically taking up lost motion in the operating means.
17. In a printing machine, a printing couple embodying a movable member, op-

erating means for unyieldably forcing the movable member on impression, and means for automatically taking up lost motion in 20 the operating means.

18. A printing press embodying a form bed and a platen, a slideable crosshead to which the platen is pivoted, and means for operating the platen to move it toward and away from the form bed and rock it over the form bed while on impression, said crosshead, when the platen is off impression, allowing the form to be readily positioned on or removed from the bed.

In testimony whereof, I have signed my name to this specification.

CARL A. KELLOGG.
